UNITED STATES PATENT OFFICE.

SIDNEY SINGLETERRY, OF DALLAS, OREGON.

CONVERTIBLE CHAIR.

1,347,127.

Specification of Letters Patent. Patented July 20, 1920.

Application filed January 28, 1920. Serial No. 354,686.

To all whom it may concern:

Be it known that I, SIDNEY SINGLETERRY, a citizen of the United States, residing at Dallas, in the county of Polk and State of Oregon, have invented certain new and useful Improvements in Convertible Chairs, of which the following is a specification.

This invention relates to combination chairs and it has for its object to provide a chair having a back section which may be swung to a position to constitute a seat for a child. In other words, it is intended to so construct an ordinary dining chair as to make the same serve, upon occasion, as a "high chair." It is the primary object of the invention to provide an improved construction of the character indicated embodying a tray and means for supporting the same above and in front of the seat, an element of the supporting means of the tray lying in position to be straddled by the child and to prevent the child from slipping downwardly beneath the tray.

It is a further object of the invention to so construct the swinging back section that constitutes the seat of the "high chair" that when the same is swung upwardly against the back proper of the chair it constitutes an element of the back and presents an ornamental appearance.

Further objects and advantages of the invention will be set forth in the detailed description which now follows:

In the accompanying drawing

Figure 1 is a perspective view of a chair constructed in accordance with the invention, and

Fig. 2 is a vertical, sectional view of said chair.

Like numerals designate corresponding parts in both of the figures of the drawing.

Referring to the drawing, 5 designates the back and 6 the seat portion of an ordinary dining chair. A swinging back section 7 has its under or outer side upholstered as indicated at 8 so that when swung upon its pivots 9 to a position where it lies between the side posts 5^a of the back 5, it will constitute an element of said back and, to outward appearances, will look like an ordinary upholstered back. While it is preferred to upholster or cover the surface of the back section 7 with leather or other suitable material, it is to be understood that this covering material may be omitted and the wood may be suitably finished, in lieu

thereof. When swung outwardly and downwardly upon pivots 9 which project laterally from the opposite rear corners of the swinging section 7, said section constitutes a seat for a child and the seat 6 of the chair then serves as a footrest for the child. When in its latter position the back section 7 is supported by two pairs of links 10^a, 11^a, the links 10^a being pivoted at their upper ends to the inner faces of the side posts 5 and being pivoted at their lower ends to the links 11^a. The links 11^a are in turn pivoted at 12 to the outer portion of the seat section 7. Ears 13 carried by the posts 5^a receive the down turned ends 14 of straps 15, said straps being carried by a tray 16. This tray has a central depending leg 17 so positioned that its lower end rests upon the seat section 7 at such a point that it may be conveniently straddled by the child, and will not only serve the function of supporting the outer part of the tray but will serve to prevent the child from slipping downwardly beneath the tray.

It will be understood that when the seat section 7 is folded upwardly against the back 5, the tray at 16 will be entirely removed. The pivots 9 engage keepers 18 that are secured to the inner faces of the posts 5^a and these keepers are provided with slots 19 of a shape to permit the disengagement of the pivots 9 therefrom. Thus it is possible by completely disengaging these pivots from the keepers to swing the seat section 7 upon the pivots 12 to bring the upholstered side of the section 7 uppermost.

This will cause the pivots 12 to then lie at that side of the section 7 nearest the back 5. By moving the section 7 to the dotted line position indicated at a in Fig. 2 and by supporting the outer end of said section upon a short leg b a seat is provided for a child too large to use a "high chair" but too small to use an ordinary dining chair. In other words, when in this position the section 7 serves as a seat for children of seven or eight years of age.

It is to be understood that the invention is not limited to the precise construction set forth but that it includes within its purview whatever changes fairly come within either the terms or spirit of the appended claim.

Having described my invention, what I claim is—

A device of the character described comprising in combination with an ordinary dining chair a section having one of its faces

upholstered, said sections being detachably hinged at its lower corners to the side posts of the back of the chair and being adapted to swing from a position where it lies substantially vertically between the side posts of the chair to a position where it lies substantially horizontal, links pivotally connected to each other and to the side posts of the chair and to the said section at a point upon the edges of said section remote from the hinge connections thereof, said links

serving when the said section is thrown downwardly upon its hinge connections to support said section horizontally at one level above the seat proper of the chair and serving when said section is disconnected from said hinge connections and swung over upon the pivotal connections of the links therewith to support said section at a lower level but above the seat proper of the chair. 15 20

In testimony whereof I affix my signature.
SIDNEY SINGLETERRY.
